UNITED STATES PATENT OFFICE

STANISLAW SZEWCZYK, OF PASSAIC, NEW JERSEY

SCRAPER FOR BELT-MAKING MACHINES

Application filed June 22, 1927. Serial No. 200,671.

This invention relates to improvements in belt-making machines, particularly to a scraper for the glue plates on which the parts of laminated belts are glued together, and it is the principal object of my invention to provide a scraper provided with means for yieldingly engaging the scraper knives with the plates.

Another object of the invention is the provision of a scraper having adjustable scraper knives or blades and adapted to be propelled by motor power.

A further object of the invention is the provision of a scraper guided along a track and of a construction which is simple, durable, yet efficiently operating.

A still further object of the invention is the provision of a scraper adapted to be operated from a motor and equipped with elastic belts for the transmission of the motor power to the wheels of the scraper.

These and further objects and advantages of the scraper according to my invention will become more fully known as the description thereof proceeds, and will then be specifically pointed out in the appended claims.

In the accompanying drawings, forming a material part of this disclosure:

Fig. 1 is a side elevation of the scraper constructed according to my invention.

Fig. 2 is a top plan view seen in the direction of arrows 2—2 of Figure 1.

Fig. 3 is an end view of the scraper.

Fig. 4 is a plan view of one of the scraper knives, and

Fig. 5 is an edge view thereof.

Fig. 6 is a sectional detail view on a plane passing substantially vertically through the boss and associated parts.

As illustrated, the scraper according to my invention comprises two bodies or shoes, an upper one 10, and a lower one 11 having bevelled end faces arranged at an inclination to the plates 12 and 13 respectively of the belt making machines, commonly known as the glue-plates.

The lower shoe or body 11 is connected to the upper one, 10 by means of the standards or posts 14, 15 respectively, the upper ends of which play within recesses 16, 17 in the upper

shoe 10 and slide therein. Collars 18, 19 on said rods limit their movement. In order to make the movements of the shoes or bodies 11 and 10 against the plates 13 and 12 respectively yieldingly, piston rods 20, 21 are attached at their lower ends to the lower shoe 11 and work in cylinders 22, 23 having their upper ends resting against plates 24, 25 integrally made with the underface of the shoe 10. Within these cylinders springs 26, 27 are arranged and rest with their lower ends against the ends of the pistons 20, 21 and with their upper ends against plates 24, 25.

The lower shoe 11 carries in approximately its center a boss 28 to which is secured by a pin 32 a member 30 having formed therein an elongated, longitudinally extending slot 31 through which pin 32 extends. On the pin 32 is pivoted the lower end of a lever 33, while a pin 29 is carried by and projects from the face of member 30. The lever 33 has near its lower end a plurality of semi-circular recesses 34, 35 adapted to engage over the pin 29. The end of a rod 36 is secured in the upper end of member 30 and is passed through the shoe 10 carrying at the upper face of the same a locking nut 37, while a locking nut 38 serves to lock the pin 32 in any of its adjusted positions within slot 31.

The knives or scraper blades 39 and 40 are provided with elongated slots 41', allowing the passage of adjusting screws 41 or the like for adjustably holding the blades on the beveled edges of the shoes and engage with their upper ends the inner faces of the plates 12 and 13 to scrape every particle of glue therefrom.

The shoes 10 and 11 move longitudinally to the plates 12, 13, on wheels 42, arranged in pairs on axles 43, and the axles of one pair of wheels on the upper as well on the lower shoe carry pulleys around which belts 44, 45 made from elastic material are guided which are also guided over pulleys on the shaft 46 of an electric motor 47 suspended from a bracket 48 attached to the lower face of the upper shoe 10.

Gage rods 49, 50 are guided within suitable sleeves 51, 52 and adjustably held therein by means of screws 53, 54. Their outer ends

are downwardly bent and carry lower brackets 55 adapted to travel on suitable tracks 56, while 57 is a rod connecting the end brackets of the two rods and adjustably held therein by means of screws or the like.

6 The operation of the scraper will be clearly understood from the above description, and it will be understood that the operation of lever 33 will press the knives more or less against the glue-plates according to the thickness of the coat thereon to be scraper, while the pistons and springs will provide the necessary yielding during the movement of the shoes along the plates by the motor guided by the 10 roller of the gage rods running on a track. The belts 44, 45 have a certain elasticity to follow the oscillations of the shoes. Such changes as come within the scope of the claims 15 may be made without interference with the inventive idea.

Having thus described my invention, what I claim as new, and desire to secure by Letters Patent is:

1. A scraper for belt-making machines 25 comprising a pair of shoes, adjustable scraper knives at the ends of said shoes adapted to engage the glue-plates of a belt-making machine, means for yielding pressing said shoes and their knives against said plates, means 30 for moving said shoes along said plates, and gage means for guiding the movement of said shoes.

2. A scraper for belt-making machines comprising a pair of shoes having beveled 35 end faces, knives adjustably secured to said end faces, wheels on said shoes adapted to engage the inner faces of the glue-plates of the machine, means for yieldingly connecting the shoes, means for yieldingly pressing said 40 shoes against said plates, a motor for driving said wheels, elastic transmission bands guided over pulleys on the wheel axles and on the motor shaft, a gage frame, and means on said frame adapted to travel along a track for 45 guiding the movements of said shoes.

3. A scraper of the character described, comprising a pair of wheeled shoes, a pair of pistons attached at one side to one of the 50 shoes, cylinders attached to the inner face of the other shoe, springs in said cylinders resting with one of their ends on the end of said pistons and with their opposite ends engaging the end walls of said cylinders for cushioning the movements of the shoes, and 55 a motor for moving said shoes.

4. In a scraper of the class described, the combination of two wheeled shoes having knives at their ends adapted to engage and scrape the inner faces of a pair of glue-plates 60 of a belt-making machine, with means for yieldingly guiding the shoes and their knives against said plates, means for cushioning the 65 shoes against each other, and a plurality of posts attached at one end to one of the shoes and at their opposite ends gliding within 70

depressions on the inner face of the opposite shoe, and means for moving said shoes and their knives along said plates to scrape the same.

5. In a scraper for the glue-plates of belt-making machines, the combination of a pair of wheeled shoes having bevelled ends knives attached to said bevelled ends adapted to engage and scrape the inner faces of two glue-plates of a belt making machine, with a 75 guide for said shoes, a motor to move said shoes along said plates, said guide comprising a pair of sockets on the upper face of the lower shoe, a pair of bars laterally projecting from the sockets and adjustable means 80 for locking said bars to said sockets, a bar connecting the outer ends of said laterally projecting bars, a pair of brackets on said bar, and wheels on said brackets adapted to travel along a track beside the scraper. 85

6. In a scraper of the class described a pair of shoes bevelled outer ends thereon and, knives on said outer beveled ends, adjustable and adapted to engage the inner faces of the glue-plates of a belt-making machine, a motor for moving said shoes and knives along 90 said plates, and elastic belts for transmitting the rotation of the motor axle to the axles of the shoe wheels, and a bracket for suspending said motor from one of said shoes. 95

In testimony whereof I affix my signature.

STANISLAW SZEWCZYK.
